CURT SCHRAEPLER, OF ESSEN-ON-THE-RUHR, GERMANY, ASSIGNOR TO FRIED. KRUPP AKTIENGESELLSCHAFT, OF ESSEN-ON-THE-RUHR, GERMANY.

MOUNTING FOR ELECTRODES WITH COOLED METALLIC HEAD.

1,408,406.

Specification of Letters Patent. Patented Feb. 28, 1922.

Application filed March 25, 1914. Serial No. 827,209.

(GRANTED UNDER THE PROVISIONS OF THE ACT OF MARCH 3, 1921, 41 STAT. L., 1313.)

To all whom it may concern:

Be it known that I, CURT SCHRAEPLER, residing at Essen-on-the-Ruhr, Germany, a subject of the Emperor of Germany, have 5 invented a certain new and useful Improvement in Mountings for Electrodes with Cooled Metallic Heads, of which the following is a specification.

The invention relates to metallic mountings for electrodes, with cooled metallic heads, to be suspended over the melting baths of electric furnaces, and has for its objects to attain, with such electrodes, first an easy replaceability, without detracting 10 from the value and reliability of the circuit-closure between the mounting and the head of the electrode, and second, to render it possible to protect from unpermissible heat, the electrode-mounting that contains the 15 conductor. These purposes are attained, according to the invention, by providing the electrode with a metallic, cooled head and by having both the metallic electrode-head and the appurtenant metallic electrode- 20 mounting, provided with corresponding conical carrying surfaces, so that upon the suspension of the electrode-head from above, loaded with the electrode, the effect of the 25 weight of the electrode will be to enforce such an intimate contact between these parts that from this condition alone, a safe and 30 good conductivity is insured between the electrode head and the electrode mounting to which the conductor is connected.

35 The accompanying drawing is a longitudinal sectional view showing an illustrative embodiment of the subject of the invention.

The electrode consists of a carbon cylinder 40 A and a metallic head B, which is connected with the cylinder through means of the tap b^1 and arranged in a known manner for the reception of a cooling fluid E. When in use, the electrode rests under its own weight 45 with its metallic head B, which is provided with a conical bearing surface b^2 , in a correspondingly formed metallic mounting C, which is fixed on the end of an arm D, which arm is intended to be adjustable up and 50 down upon a column, not shown. For securing the connection between the mounting C, through which the current circuit is closed,

and the electrode head B, a number of screw bolts c^1 are employed, which are jointed to the mounting C in the manner shown in the 55 drawing.

Under the action of the inherent weight of the electrode a high pressure exists between the electrode head B and the mounting C upon the conical bearing surfaces b^2 , 60 which is found in practice to insure a thoroughly reliable and practicable circuit closure. When the electrode is required to be raised from its bearing for the purpose of replacing the carbon cylinder, it is only 65 necessary to release the connection established by the bolts c^1 in order to permit raising of the electrode.

I claim:

1. A metallic mounting for a vertically arranged electrode, designed for electrical furnace purposes, said electrode being provided with a cooled metallic head, said metallic head being supported by said mounting and being adapted to support the 75 weight of the electrode; said mounting and head being constructed with corresponding conical bearing surfaces to insure intimate electrical contact by means of the weight of the electrode solely.

2. A metallic mounting for a vertically arranged electrode, designed for electrical furnace purposes, said electrode being provided with a cooled metallic head, said metallic head being supported by said mounting and 85 being adapted to support the weight of the electrode; said mounting and head being constructed with corresponding conical bearing surfaces to insure intimate electrical contact by means of the weight of the 90 electrode solely; and means connected to said head and mounting for securing the mechanical and electrical connection between said parts; said means comprising screw bolts jointed to one of said parts and 95 engaging in recesses of the other part.

The foregoing specification signed at Barmen, Germany, this 4th day of March, 1914.

CURT SCHRAEPLER. [L. S.]

In presence of—

HELEN NUFER,
ALBERT NUFER.
